UNITED STATES PATENT OFFICE.

CARLO BONZANIGO, OF BASEL, SWITZERLAND.

GATE FOR LOCKS, WEIRS, AND THE LIKE.

1,136,765.

Specification of Letters Patent.

Patented Apr. 20, 1915.

Application filed November 29, 1913. Serial No. 803,677.

To all whom it may concern:

Be it known that I, CARLO BONZANIGO, a citizen of Switzerland, residing at Basel, Switzerland, have invented certain new and 5 useful Improvements in Gates for Locks, Weirs, and the like, of which the following is a specification.

My invention relates to improvements in gates for locks, weirs and the like, and more 10 particularly in lock or weir gates which are made in sections adapted to be lifted by a single hoisting mechanism.

The object of the improvements is to provide a lock gate of this class and its hoisting mechanism, in which when opening the 15 gate the upper section is first moved into opening position and thereafter the lower section.

With this object in view my invention 20 consists in the matters to be described hereinafter and particularly pointed out in the appended claims.

For the purpose of explaining the invention two examples embodying the same have 25 been shown in the accompanying drawings, in which the same letters of reference have been used in all the views to indicate corresponding parts.

In said drawings Figures 1 to 3, are vertical cross-sections of the gate showing the 30 sections thereof in different positions, Fig. 1 showing both sections in closed position, Fig. 2 showing the upper section in open and the lower section in closed position, and 35 Fig. 3 showing both sections in open position. Fig. 4, is a plan view showing the hoisting mechanism, Figs. 5 to 7 are cross-sections of a modification of the gate similar to those shown in Figs. 1 to 3, and Fig. 8, 40 is a plan view of the hoisting mechanism of the gate shown in Figs. 5 to 7.

Referring to the example illustrated in Figs. 1 to 4, my improved lock or weir gate 45 consists of a lower section *e* and an upper section *a* which are movable independently of each other. As shown, the sections are connected to the opposite ends of flexible tension elements such for example as chains *b*, *d* trained over suitable driving pulleys 50 such as sprocket wheels *c* adapted to be operated by a suitable hoisting mechanism such as gear wheels *o* meshing with pinions *p* mounted on a shaft *s* and adapted to be rotated from a suitable motor *r* through the 55 intermediary of a worm gearing *q*.

When both sections of the gate are in the

closed position shown in Fig. 1, the part *b* of the chain from which the upper section is suspended is stretched, while the part *d* which is attached to the lower section is slack. If it is desired to open the gate, the sprocket wheels *c* are rotated by their driving mechanism so as to lower the upper section *a*, while for the present the lower section *e* remains at rest. The degree of the slackness of the part *d* of the chain is such, that the said part is stretched when the section *a* is in its lowermost position shown in Fig. 2. In this position of the gate sections the upper section *a* finds a support on arms *t* provided on the lower section. Therefore, when the hoisting mechanism is further operated in the same direction as before, the lower section which is thereby elevated carries along the upper section *a* until both 75 arrive in the position shown in Fig. 3, in which the lock is perfectly open. When closing the gate the hoisting mechanism is operated in the opposite direction. At first both sections of the gate are lowered into 80 the position shown in Fig. 2, whereupon by further operating the hoisting mechanism the upper section is lifted into the position shown in Fig. 1, while the lower section *e* remains at rest.

In the example shown in Figs. 5 to 8 the upper section *f* of the gate is hinged to the lower one *g*. Chains *h* are connected to the upper ends of brackets *f'* secured to the upper section *f*, and chains *k* are attached 90 to the lower section *g*. To show that it is not necessary to connect the sections of the gate to the opposite ends of the same chain trained over the same sprocket wheel, as has been described with reference to Figs. 95 1 to 4, Figs. 5 to 8 show the said sections as being connected to separate chains each of which is trained on a sprocket wheel *i*, *l* respectively of its own and is attached with its free end to a fixed part *u*. The driving 100 mechanism connected with the said sprocket wheels may be the same as in the example shown in Figs. 1 to 4. The overhanging ends *m* and *j* of the chains may be kept in suitable boxes (not shown).

The operation of the gate shown in Figs. 5 to 8 is the same as that of the gate shown in Figs. 1 to 4, and it will readily be understood from the figures showing the sections in their different positions. From the description it will be understood that a single 110 hoisting mechanism is provided in combina-

tion with both sections of the gate. Therefore, if it is desired to open the gate in part only, as is ordinarily necessary in the operation of the gate, the upper section can be 5 opened to the desired extent. For opening both sections the same hoisting mechanism is used which is operated in the same direction as before. If the size of the upper section is sufficient, the lower section is opened 10 only in exceptional cases. When operating the gate, the upper section is always opened prior to the lower one. Therefore the large amount of water is discharged through the upper section of the gate, so that the high 15 pressure of the water is removed before the lower section is opened, so that the floor of the lock or the like is saved from injury caused by the high pressure of the water flowing over the same, and on the other hand 20 floating bodies such as leaves, wood blocks, pieces of ice, and the like are removed together with the excess of water.

While in describing the invention reference has been made to particular examples 25 embodying the same, I wish it to be understood, that my invention is not limited to the general arrangement and construction of the parts shown in the drawings, and that various changes may be made within the 30 scope of my invention. For example, instead of the chain and sprocket mechanism provided for lifting the gate other suitable means may be provided.

I claim herein as my invention:

- 35 1. In a gate for locks weirs and the like, the combination with upper and lower gate sections, of a single hoisting mechanism connected with said sections for operating the same in opposite directions, and means on 40 said lower section operative after the upper section has been lowered into opening position and arranged to carry the upper section along as the lower section is raised to the fully open position of the gate.
- 45 2. In a gate for locks weirs and the like, the combination with upper and lower gate sections, of a single hoisting mechanism comprising rotary members, lifting elements

connected with said rotary members for operation in opposite directions and connected 50 respectively with the said gate sections, the element connected with the lower section being operative after the upper section has been lowered into opening position, and means on said lower section for carrying the 55 upper section along.

3. In a gate for locks weirs and the like, the combination with upper and lower gate sections, of a single hoisting mechanism comprising rotary members, flexible lifting 60 elements connected with said rotary members for operation in opposite directions and connected respectively with the said gate sections, the element connected with the lower section being operative after the upper section has been lowered into opening 65 position, and means on said lower section for carrying the upper section along.

4. In a gate for locks, weirs, and the like, the combination of upper and lower gate 70 sections capable of independent movement one relatively to the other, means on the lower section to engage and support the upper section, and actuating mechanism which when operated in one direction will 75 first move the upper section alone to its open position and will then move both sections in the opposite direction, to fully open the gate.

5. In a gate for locks, weirs, and the like, the combination of upper and lower gate 80 sections of which the upper section is capable of a limited movement relatively to the lower section, and operating mechanism having individual connections to the respective sections, said mechanism, when operated continuously in one direction, effecting 85 first a movement of the upper section in one direction and then a movement of both sections in the opposite direction.

In testimony whereof, I have signed this 90 specification in the presence of two subscribing witnesses.

CARLO BONZANIGO.
